METAL WINDOW

Emil K. Geyser, Pittsburgh, Pa., assignor to E. K. Geyser Company, Pittsburgh, Pa., a corporation of Pennsylvania

Application September 28, 1955, Serial No. 537,142

7 Claims. (Cl. 189—75)

This invention relates to windows having stationary metal frames, and more particularly to a frame that can be inserted in a window opening from the outside of the building.

Most metal window frames have to be inserted in window openings from inside of the building. In some cases, this is difficult to do because of interfering posts or scaffolding which do not leave enough space for manipulating the frame into place. Also, being inserted from the inside, trim strips have to be attached to the outside of the frame after it is in position.

It is among the objects of this invention to provide a window having a metal frame which can be mounted in place from the outside of the window opening, which can be installed quickly and easily, which is easy to manufacture, which is held in permanent position, and to which inside trim strips can be quickly and easily attached if desired.

In accordance with this invention angle bars are disposed in a window opening where they extend across its top and bottom and down its sides. Each angle bar has a front flange projecting away from the adjoining wall at the front of a rearwardly extending flange. Clips in the window opening are secured to the wall behind the bars and have front ends overlapping the rearwardly extending flanges of the bars to clamp the bars in place. A metal window frame in the opening is surrounded by front and rear flanges on opposite sides of the angle bars. The frame engages the front of the bars and has a front portion provided with an inwardly facing slot that is adapted to receive the periphery of a pane of glass. The clips have rear ends projecting away from the adjoining wall in front of the rear flanges of the frame. The flanges at the top and sides of the frame are spaced rearwardly from the rear ends of the clips. The rear ends of the clips at the top and sides of the opening are overlapped by locking members which engage the front of the rear flanges of the frame. The locking members are detachably connected to the clips to hold the clips against the frame flanges behind it. At the time this frame is being installed in a window opening, the locking members have not yet been attached to the clips. The frame is held in an inclined position with its top swung out away from the building, and then its bottom is inserted in the window opening and pushed back until it engages the front of the bottom angle bar. The top of the frame then is swung back into the window opening until the front portion of the frame engages the front of the top and side angle bars. Assuming that the angle bars have been correctly located, the frame now will be in vertical position. The locking members then are fastened to the rear ends of the clips in order to hold the frame in place. Trim strips can be applied to the inside or rear of the window by providing them with outside flanges that are pushed forward between the surrounding wall and leaf springs carried by the rear ends of the clips. The springs tightly engage the flanges of

2

the trim strips and hold the strips against the rear flanges of the window frame.

The preferred embodiment of the invention is illustrated in the accompanying drawings, in which

Fig. 1 is a front or exterior view of the window;

Fig. 2 is an enlarged horizontal section of the frame taken on the line II—II of Fig. 1; and

Fig. 3 is an enlarged fragmentary vertical section of the frame taken on the line III—III of Fig. 1.

Referring to the drawings, a rectangular window opening is formed in the wall 1 of a building, which may be constructed from any suitable building material. At the top of the opening there is the customary metal lintel 2. Extending across the top of the window opening is a metal angle bar 3, which has a horizontal flange engaging flat against the lintel, and its other flange extending down away from the front edge of the horizontal flange. Similar angle bars 4 extend down the sides of the opening against the adjoining wall. A like bar 5 also extends across the bottom of the opening, where it may be supported at intervals by metal shims 6. All of these angle bars are fastened in place by means of metal clips 7 secured to the surrounding wall.

Each clip is a short rigid strip of metal, the front portion of which overlaps the rearwardly extending flange of the adjoining bar. Behind the bar, the clip is provided with a slot 9, through which a stud 10 extends and fastens the clip to the adjoining wall. The bars and clips are locked together by turning the rear edges of the bars away from the wall and into transverse recesses 11, with which the clips are provided. These recesses can be produced by forming a crimp in each clip. Each recess is located so that its front wall will engage the inturned edge of the bar while the front end of the clip will substantially engage the front flange of the bar. A great advantage of fastening the bars in place by clips is that the bars do not have to be drilled, and the studs that hold the clips do not have to be located in any particular locations. For example, the line of stud-receiving holes in the lintel can be punched before the lintel is installed and need not register with any other holes because the clips can be placed anywhere along the lintel. The slots in the clips permit sufficient adjustment of the clips lengthwise to allow the angle bars to be located in correct position. The rear ends of the clips are turned inward into the window opening away from the surrounding wall for a purpose that will be described presently.

The prefabricated window frame that is mounted in this window opening is formed from head and sill members 13 and 14 joined by vertical side members 15 or jambs; all welded or otherwise fastened together rigidly at the corners of the frame before it is set into place. All of these frame members may be identical to one another, except in length. Each of the frame members is of general channel shape with front and rear flanges. The front flanges 17 extend outward in overlapping relation with the front flanges of the angle bars. Just behind the front flanges of the frame it is provided with a slot 18 that opens into a recess 19. The slot is designed to receive the periphery of a pane of glass 20 (Fig. 1), and the recess is filled with putty to seal the glass in place. Near the outer edges of the front flanges of the frame there are rearwardly extending ribs 21 that engage the front of the angle bars at the top and sides of the opening. The bottom angle bar, however, is located farther back in the opening than the others, so that the web or wall of the bottom frame member behind the putty recess can rest on top of the front flange of the bar as shown in Fig. 3. The back part of the frame rests on the upturned rear ends of the bottom clips. The clips are of such length that the bottom of the frame cannot

be moved either forward or backward on the supporting clips and angle bar.

The top and sides of the frame are held back against the adjoining angle bars by means of locking members 23 connected to the rear ends of the clips at the top and sides of the opening. Each locking member is an L-shaped piece that overlaps the rear surface of the in-turned rear end of the adjoining clip. The inner ends of the locking members engage the front surfaces of the rear flanges 24 of the frame, which do not project out as far as the position of the inner ends of the clips. The locking members are detachably connected to the clips by means of screws 25. Preferably, the outer ends of the locking members are spaced slightly from the clips so that when the screws are tightened, the inner ends of the locking members will be forced back against the frame to hold the front of it tightly against the angle bars.

The frame is installed before the locking members 23 are fastened to the clips 7. To install the frame, it is picked up in front of the window opening outside of the building, and its top end is tilted away from the building. The bottom of the frame is then inserted into the opening and lowered until it rests on the bottom angle bar 5. The bottom of the frame is pushed back over the bar as far as possible into the window opening, as indicated in Fig. 3, the tilted position of the frame permitting the bottom rear flange 24 of the frame to pass over the up-turned rear ends of the bottom clips. The top of the frame is then swung back into the window opening until the top and side ribs 21 engage the front of the top and side angle bars. The in-turned rear ends of the clips will not interfere with this movement of the frame because its rear flanges are short enough to avoid striking the clips, as is obvious in Figs. 2 and 3. With the frame now in upright position in the window opening, locking members 23 can be attached to the clips by means of screws 25 to hold the frame in position with its front part tightly engaging the angle bars.

If it is desired to fill in the space between the back of the frame and the top and sides of the window opening, which generally will be the case, angular leaf springs 27 may be attached to clips 7 at the same time that the locking members are attached, by clamping them between the locking members and clips. The free portions of the springs extend back along the adjacent wall and have loops at their rear ends. Trim strips 28 are provided, which will engage the back of the frame and the surrounding wall of the window opening. Each strip has a forwardly projecting outer side flange 29, which preferably has a beveled front edge and a notch 30. The strip is mounted in place by pushing it forward along the wall, so that its beveled edge will bend the adjoining springs away from the wall. When the strip is in correct position against the back of the frame, the looped ends of the spring will snap into the notch and hold the trim strip in place. A tighter connection is formed between the inner edge of the strip and the window frame if the outside flange of the strip has a rib 31 extending along it to space it from the wall. The pressure of the springs against the strip flange in front of the rib will tend to rock the strip on the rib and press the inner edge of the strip tightly against the window frame.

It will be seen that this window frame not only can be inserted from outside of the window where there is plenty of room to work, but also that it is held in place in a simple manner. The space between the front of the frame and the surrounding wall can be filled with caulking material (not shown) in the usual way. The window pane can be mounted in the frame either before or after the frame has been installed. The trim strips inside of the building can be quickly snapped in place. A major advantage of this window is that all four sides of the frame can be made from the same stock, and the sup-

porting members around the frame can be installed quickly with studs in random locations.

According to the provisions of the patent statutes, I have explained the principle of my invention and have illustrated and described what I now consider to represent its best embodiment. However, I desire to have it understood that, within the scope of the appended claims, the invention may be practiced otherwise than as specifically illustrated and described.

10 I claim:

1. The combination with a wall having a window opening through it, of angle bars in the opening extending across its top and bottom and down its sides, each angle bar having a front flange projecting away from the adjoining wall at the front of a rearwardly extending flange, clips in said opening secured to the wall behind said bars and having front ends overlapping the rearwardly extending flanges of the bars to clamp the bars in place, a metal window frame in said opening surrounded by front and rear flanges on opposite sides of the angle bars, the frame engaging the front of said bars, and locking members fastened to the clips at the top and sides of the opening and engaging the front of the rear flanges of the frame; whereby said frame can be installed in said opening from the front, before said locking members are fastened in place, by first placing the frame in an inclined position with its bottom flanges straddling the bottom angle bar and clips and then swinging the top of the frame back into said opening until the frame is upright against the front of the angle bars.

2. In the combination recited in claim 1, the rear edges of the angle bars being turned away from the adjoining wall, and each clip being provided with a transverse recess receiving the rear edge of the adjoining bar to lock the bar and clip together.

3. In the combination recited in claim 1, leaf springs supported by the rear ends of the clips and extending rearwardly therefrom, and trim strips in said window opening engaging the back of the rear flanges of the frame and pressed against the surrounding wall by said springs.

4. In the combination recited in claim 1, leaf springs supported by the rear ends of the clips and extending rearwardly therefrom, and trim strips in said window opening engaging the back of the rear flanges of the frame and having side portions projecting forward between said springs and the surrounding wall, said side portions being provided with notches receiving the rear ends of the springs, whereby the springs press the trim strips against said wall and hold them against the window frame.

5. The combination with a wall having a window opening through it, of angle bars in the opening extending across its top and bottom and down its sides, each angle bar having a front flange projecting away from the adjoining wall at the front of a rearwardly extending flange, clips in said opening secured to the wall behind said bars and having front ends overlapping the rearwardly extending flanges of the bars to clamp the bars in place, a metal window frame in said opening surrounded by front and rear flanges on opposite sides of the angle bars, the frame engaging the front of said bars, the clips having rear ends projecting away from the adjoining wall in front of the rear flanges of said frame, the rear flanges of the frame at its top and sides being spaced rearwardly from the rear ends of the clips, locking members overlapping the rear ends of the clips at the top and sides of the opening and engaging the front of the rear flanges of the frame, and means fastening the locking members to the clips to hold said members against the frame flanges behind them; whereby said frame can be installed in said opening from the front, before said locking members are fastened in place, by first placing the frame in an inclined position with its bottom flanges

70 straddling the bottom angle bar and clips and then swinging the frame back into said opening until the frame is upright against the front of the angle bars.

75

ing the top of the frame back into said opening until the frame is upright against the front of the angle bars.

6. In the combination recited in claim 5, the outer ends of the locking members being spaced from the clips to permit the inner ends of said members to be pressed 5 tightly against the frame flanges behind them.

7. In the combination recited in claim 5, the bottom of the window frame between its flanges resting on the front

flange of the bottom angle bar and the rear ends of the bottom clips.
